(57) **CLAIM**

I claim the ornamental design for a child potty, as shown and described.

DESCRIPTION

FIG. 1 is a top perspective view of a child potty showing my new design;

FIG. 2 is front elevational view thereof;

FIG. 3 is rear elevational view thereof;

FIG. 4 is a right elevational view thereof;

FIG. 5 is a left elevational view thereof;

FIG. 6 is a top plan view thereof;

FIG. 7 is a bottom plan view thereof;

FIG. 8 is a cross sectional view thereof, taken along the lines 8-8 in FIG. 6; and,

FIG. 9 is a rear right side prospective view thereof, the broken lines depicting portions of a child potty form no part of the claimed design.
